UNITED STATES PATENT OFFICE.

CHARLES R. COUP, OF MCKEESPORT, PENNSYLVANIA.

MILK BOTTLE.

Application filed March 2, 1927. Serial No. 172,063.

This invention relates to special receptacles and more particularly to a milk bottle. Milk bottles of a conventional construction are formed with an internal seat adjacent 5 their open upper ends to receive a cardboard closure cap for the bottle and it has been found that, when removing one of these caps by means of a sharpened instrument thrust through the cap, the cap will very often be crumpled and forced downwardly into the neck and cause the milk to spurt upwardly and spoil the clothing of the person opening the bottle. Some caps are provided with removing tabs so that they may be readily lifted but the caps often tear loose. It has also been proposed to provide the mouth of the bottle with a recess leading from the seat entirely through the wall of the bottle but this has been found unsatisfactory as it 10 forms a break in the outer side face of the bottle wall and very often will cause cuts upon the fingers of a person handling the bottles and in addition allow dirt and dust to readily enter the recess and work under the closure cap of the bottle.

Therefore, one object of the invention is to provide a milk bottle formed with a recess which will permit access to the margin of a closure cap without forming a break in 15 the outer side surface of the bottle neck.

Another object of the invention is to so form the recess that an outer marginal wall will be provided which will serve to exclude dirt and dust and also constitute a fulcrum 20 upon which a finger or removing tool may be rocked in order to readily pry the cap out of the bottle neck.

The invention is illustrated in the accompanying drawing, wherein

40 Fig. 1 is a view showing a milk bottle of the improved construction partially in side elevation and partially in longitudinal section;

45 Fig. 2 is a top plan view of the milk bottle, and

Fig. 3 is a perspective view of the upper portion of the milk bottle.

The improved milk bottle, which is indicated by the numeral 1, is formed of glass 50 and has its upper end portion tapered in the usual manner to form a neck 2 which is open at its upper end and externally thickened to form a bead 3 to prevent the bottle from easily slipping out of the hand when grasped 55 and lifted by its neck in the usual manner.

At its upper end the neck is formed with an internal circumferentially extending ledge or seat 4 upon which the cardboard closure cap 5 rests when applied to the bottle. The construction so far described is conventional 60 and, as previously set forth, it is often difficult to remove the cap without forcing it downwardly into the bottle and causing the milk to spurt upwardly.

In order to allow the cap to be easily removed, I have provided the bottle neck with a recess 6 which is cut through the beaded upper end thereof from its inner surface but terminates in spaced relation to the outer side face of the bottle neck thereby leaving 65 a portion constituting an outer marginal wall 7 for the recess. The recess 6 is of such depth that its bottom is flush with the surface of the seat 4 and, therefore, the peripheral edge face of the cap will be exposed in the recess and a finger nail or the pointed end of a lifting implement can be easily forced under the cap. The wall 7 is of such height that its upper edge is slightly below the upper edge face 8 of the bottle 70 neck and is slightly rounded transversely in order to provide a smooth edge not liable to cut the fingers and also not liable to be easily broken.

When the bottle is in use, it is filled with 75 milk and the cardboard cap applied in the usual manner. In order to remove the cap, it is merely necessary to place a thumb or finger in the recess 6, as indicated in Fig. 1, with the nail resting upon the upper edge of 80 the wall 7 and the outer end of the nail engaged beneath the portion of the cap extending across the inner end of the recess. The finger can then be rocked upon the wall and the cap will be lifted off the seat without danger of its being forced downwardly 85 into the milk. After the cap has been removed, the milk can be poured from the bottle and the recess will serve as a pouring spout. By this arrangement the cap can be 90 easily removed and the wall will serve not only as an outer wall for the recess to prevent dust and dirt from readily accumulating in the recess but also serve as a fulcrum 95 for a finger or pointed implement employed to remove the cap. As previously explained, the wall further prevents the formation of a break in the outer surface of the beaded upper end of the bottle neck and prevents 100 the formation of sharp edges at the outer 105 edge of the recess. The recess is formed in the neck 110

ends of the bottom and end walls of the recess which might cause the hands to be cut when handling the bottle.

Having thus described the invention, I claim:

1. A receptacle open at its top and adjacent its upper end having its wall formed with an internal circumferentially extending cap receiving seat, the upper end of the receptacle being formed with a recess leading from the upper edge and inner surface of the wall of the receptacle and communicating with said seat with its bottom flush with the seat, said recess terminating in spaced relation to the outer surface of the receptacle wall to provide a lip spaced from the periphery of a cap resting upon the seat

and constituting an outer marginal wall for the recess and adapted to serve as a fulcrum when removing a cap.

2. A bottle having a cap receiving seat formed upon the interior of the neck thereof and a recess leading from the inner surface of the neck between the seat and upper end of the bottle and terminating in spaced relation to the outer surface of the neck to provide an outer marginal wall for the recess, the said marginal wall of the recess having its upper edge disposed in a plane below the upper edge face of the bottle neck but above the upper surface of a cap placed in the bottle neck upon the seat.

In testimony whereof I affix my signature.

CHARLES R. COUP. [L. S.]
